United States Patent Office

Des. 211,417
Patented June 11, 1968

211,417

CAMERA

Lucien Antoine Regis Bouchetal de la Roche,
1 Place Jules Ferry, Lyon, France

Filed Aug. 25, 1967, Ser. No. 8,396

Claims priority, application France Mar. 1, 1967

Term of patent 14 years

(Cl. D61—1)

FIG.1

FIG.2

FIG.3

FIG.4

FIG. 1 is a front perspective view of a camera, showing my new design.

FIG. 2 is a rear elevational view thereof.

FIG. 3 is an end elevational view from the right side with respect to the user of the camera, the left end elevational view being substantially a mirror image of the right end view.

FIG. 4 is a bottom plan view thereof.

I claim:

The ornamental design for a camera, substantially as shown and described.
